UNITED STATES PATENT OFFICE.

LOCKE ATWELL, OF SELMA, ALABAMA.

LIFTING-JACK.

1,244,406.

Specification of Letters Patent. Patented Oct. 23, 1917.

Application filed April 28, 1916. Serial No. 94,188.

To all whom it may concern:

Be it known that I, LOCKE ATWELL, a citizen of the United States, residing at Selma, in the county of Dallas and State of Alabama, have invented a new and useful Improvement in Lifting-Jacks, of which the following is a specification, reference being had to the accompanying drawing.

My improvement relates particularly to 10 lifting jacks comprising a base section and a plunger or head section and a screw arranged in operative relation with said sections for driving them endwise relative to each other and mechanism for turning said 15 screw, said mechanism comprising ratchet members operated by a hand lever.

The purpose of my invention is to automatically put said ratchet mechanism out of action when the screw has moved the 20 plunger through a chosen distance while lifting a load. While the screw is being turned for lifting a load, it is desirable that the screw be not turned so far as to disengage altogether from the plunger nor 25 even so far as to leave only a small number of turns of the thread in engagement with the plunger, for it has repeatedly been shown in practice that under such condition the weight of the load is apt to strip the 30 threads and allow the hoisted body to fall and further damage the lifting jack and to injure the workmen. In this connection, it is to be observed that my improvement is intended to be applicable specially to lifting 35 jacks used for lifting railway cars and other heavy bodies ranging from twenty-five tons to one hundred tons or more.

Efforts have heretofore been made to prevent excessive lifting of the plunger, such 40 efforts being directed to applying means for indicating to the eye or the ear when the screw has turned to the danger limit. But such means have left it possible for the operator to disregard, intentionally or 45 unintentionally, the indication. In my improved structure, the members of the ratchet mechanism become automatically disengaged from each other when the chosen movement of the plunger has been attained, 50 so that turning of the screw ceases, although the operator continues to oscillate the hand lever.

In the accompanying drawings.

Figure 1 is a side elevation of a lifting

jack embodying my improvement, portions 55 being broken away;

Fig. 2 is a sectional elevation looking at the apparatus from the right as shown in Fig. 1;

Fig. 3 is a section on the line, 3—3, of 60 Fig. 2, looking toward the right;

Fig. 4 is a horizontal section on the line, 4—4, of Figs. 1 and 2;

Fig. 5 is a section on the line, 5—5, of 65 Fig. 2, looking toward the right;

Fig. 6 is a section on the line, 6—6, of 70 Fig. 4, looking toward the left;

Fig. 7 is a section on the upper portion of a plane which is perpendicular to Fig. 2 and cuts said figure along its upright axis, 75 the view being toward the left;

Fig. 8 is an elevation of the connecting bar shown detached and in the position occupied in Fig. 2;

Fig. 9 is a horizontal section on the line, 75 9—9, of Fig. 8;

Fig. 10 is a rear elevation of the pawl detached from the other mechanism;

Fig. 11 is a section on the line, 11—11, 80 of Figs. 1 and 4, looking in the direction of the arrow.

Referring to said drawings, A is the base and B is the plunger. Said base and said plunger are made telescoping in the usual manner. Either of these members may be 85 directed upward when the mechanism is set in the upright position for work. The plunger is tubular and interiorly screw threaded and receives a screw, C. The lower end of said screw rests in a bearing, 90 A¹, in the lower portion of the base, A. Immediately above said bearing, the screw is surrounded by a bevel gear wheel, C¹, having its teeth directed upward and which is keyed to the screw. By turning said 95 bevel gear wheel in the proper direction, the screw is made to drive the plunger upward.

At its front, the base, A, has an opening to which is secured a wall section, A², by 100 means of four bolts, A³. In said wall section is a bearing, A⁴, which is horizontal and perpendicular to the axis of the screw. In said bearing is a rotary shaft, C³, having its ends projecting through said bearing. 105 The inner end of said shaft supports a bevel gear wheel, C², which is rigid on said shaft. The rotation of said shaft causes the rota-

tion of the bevel gear wheel, C³, and the screw, C.

To prevent the plunger from turning, it is provided on its exterior with an upright channel, B¹, which receives a key, A⁵, having a shank, A⁶, extending horizontally outward through the wall of the base, A, and receiving a nut, A⁷.

On the outer end of the shaft, C³, is applied the ratchet mechanism, D, whereby said shaft is turned. Said mechanism comprises a group of members which will be next described.

A body, D¹, surrounds the shaft, C³, and may rock or rotate on said shaft in a plane which is upright and to which said shaft is perpendicular. Said body has a socket approximately perpendicular to the shaft, C³, and adapted to receive a hand lever, D³. Said body has a chamber extending upward and downward through the body and adapted to receive a ratchet wheel, D⁴. The portion of said shaft within said wheel is polygonal in order that said shaft and said wheel may rotate in unison while, as above stated, the body, D¹, is free to rock or rotate on the shaft, C³, excepting when engagement between said body and said wheel is made by means of the pawl, D⁵.

Said pawl is an upright member located within the body, D, at the right of the ratchet wheel and reciprocable upward and downward, perpendicularly to the hand lever, D³, and adapted to be held at either of two elevations by a yielding tooth, D⁶, seated in a horizontal barrel, D⁷, and surrounded by an expanding coiled spring, D⁸, bearing against the inner end of said barrel and against a shoulder, D⁹, on said tooth and normally holding said tooth at its outer limit and in one or the other of two notches, D¹⁰, in the rear face of the pawl.

It will be observed that the path of reciprocation of the pawl, D⁵, is approximately tangential to the ratchet wheel, D⁴, and that any part of said pawl which approaches the line which is the axial line of the hand lever and cuts the axis of the ratchet wheel must at the same time approach said wheel, and, conversely, any part of said pawl which is moved away from said axial line must move away from said wheel. On the pawl are two jaw faces directed toward the ratchet wheel, one being above said axial line on the middle horizontal line of the ratchet wheel, and the other of said jaw faces being below said line. The upper of said jaw faces is provided with teeth, D¹¹, similar to the teeth on the jaws of a pipe wrench. The lower of said jaw faces has similar teeth, D¹². Both of said jaw faces are inclined, the upper part of the jaw face and the lower part of the lower jaw face being extended toward an upright line cutting the axis of the ratchet wheel. Thus the

portions of said pawl bearing said jaw faces are wedge-form, and when the pawl is moved upward relative to the body, D¹, the upper jaw face moves away from the ratchet wheel while the lower jaw face moves toward the ratchet wheel; and when the pawl is moved downward relative to the body, D¹, the lower jaw face moves away from the ratchet wheel and the upper jaw face moves toward the ratchet wheel. When the pawl is in its lower position, the yielding tooth, D⁶, being then in the upper notch, D¹⁰, the upper jaw face rests in engagement with the ratchet wheel, the lower jaw face being entirely away from said wheel. The particular elevation of the pawl is determined by the yielding tooth, D⁶. When strain is applied tending to move the pawl endwise, one of the oblique faces of the notch, D¹⁰, presses against the tooth, D⁶, and tends to force the latter upward into the barrel, D⁷, against the resistance of the coiled spring, D⁸. When the pawl is in its lower position, the tooth, D⁶, being in the upper notch, D¹⁰, and the hand lever, D³, is pressed downward, the portion of the body, D¹, at the opposite side of the ratchet wheel axis will rise and lift the pawl, the latter slipping on the ratchet wheel. When the hand lever is lifted, the opposite end of the body, D¹, is moved downward, and the portion of the pawl bearing the upper jaw face is wedged or jammed between the ratchet wheel and the opposite wall of the body, D¹, such engagement being thus made by the pawl and the ratchet wheel as will compel the partial rotation of said wheel in unison with the downward movement of the pawl. When the pawl is in its upper position, the tooth, D⁶, being in the lower notch, D¹⁰, the above-described actions of the pawl relative to the ratchet wheel are reversed, the pawl becoming wedged or jammed during upward movement of the adjacent end of the body, D¹.

On the upper end of the pawl is an arm, D¹³, which extends to the right along the rear of the body, D¹, and above the bearing, A⁴. Since the pawl is in its lower position when it is to make engagement for turning the shaft, C³, for driving the plunger upward, the ratchet mechanism can be reversed by pushing said arm, D¹³, upward, sufficiently to disengage the teeth, D¹¹, of the pawl from the ratchet wheel, D⁴, when said body, D, turns in either direction, the tooth, D⁶, remaining in the upper notch, D¹⁰.

Surrounding the portion of the bearing, A⁴, between the body, D¹, and the wall section, A², is a sleeve, E, which is slidable endwise on said bearing. The rear end of said sleeve normally bears against the wall section, A². The front end of said sleeve is cut slanting to form an annular cam face, E¹, bearing against a cam face, D¹⁴, on the arm, 125

D¹³ of the pawl, when said arm is in its lower position. At opposite sides of the bearing, A⁴, the sleeve, E, has a stud, E², projecting rearward from the rear face of said sleeve loosely through the wall section, A², to a cam face, E³, on a cam ring, E⁴, surrounding the bearing, A⁴, between the wall section, A², and the gear wheel, C², said ring being rotatable on said bearing and held against forward or rearward movement by said wall section and said wheel, C². Each of said cam faces, E³, is so positioned as to normally receive the adjacent stud, E², against the innermost portion of said cam face, so that when said cam ring is partially rotated contra-clockwise, the cam faces, E³, will force said studs, E², outward, whereby the sleeve, E, is forced outward and the cam face, E³, forces the arm, D¹³, upward with sufficient force to carry the pawl upward far enough to disengage the teeth, D¹¹, from the ratchet wheel so that the latter will turn freely in either direction, the yielding teeth, D⁶, retreating a little while the pawl is thus raised.

The cam ring, E⁴, is connected with the plunger by means of the connecting bar, E⁵, which is arranged to be lifted by the plunger while the latter is moving into its upper limit. In its outer face, the plunger has an upright channel, B², to receive the body of the connecting bar. The lower end of the connecting rod is turned horizontally and has a fork, E⁶, which receives a stud, E⁷, projecting outward radially from the cam ring, so that when the connecting bar, E⁵, is moved upward or downward said stud, E⁷, is correspondingly moved upward or downward and the cam ring is correspondingly partially turned. The inner face of the upright portion of the connecting bar has an upright channel, E⁸, terminating a little below the upper end of said bar and receiving a stud, B³ (Fig. 7), located in the channel, B², of the plunger. The parts are so proportioned as to bring the upper end of the bar, E⁵, into the upper end of the channel, B², when the plunger and said bar and the stud, E⁷, on the cam ring are in their lowest or rest positions; and the stud, B³, is so positioned in the channel, B², as to make engagement in the upper end of the channel, E⁸, a little before the plunger reaches its upper limit, whereby the connecting bar is lifted sufficiently to lift the stud, E⁷, and turn the cam ring, E⁴, sufficiently to drive the sleeve, E, outward and cause the cam face, E³, on said sleeve to force the arm, E¹³, and the pawl, D⁵, upward far enough to disengage the teeth, D¹¹, of the pawl from the ratchet wheel.

The ratchet mechanism is now out of action and must so remain until the pawl, D⁵, has been forced farther upward into its upper working position. For accomplishing

this, the operator applies force to the pawl, D⁵, sufficient to compel the yielding positioning tooth, D⁶, to retreat out of the upper notch, D¹⁰, and again move forward into the lower notch, D¹⁰, when the bar has ascended 70 into its upper position. Now the ratchet mechanism is adjusted for driving the screw, C, in the reverse direction and move the plunger, B, downward. When the plunger approaches its lower limit, the upper 75 end of the connecting bar, E⁵, is engaged in the upper end of the slot, B², whereby said bar is driven downward to its lower or rest position. During such movement, the fork, E⁶, moves the stud, E⁷, downward into the 80 lower or rest position, whereby the cam ring is partially turned and space is made for the inward movement of the studs, E², and the sleeve, E, to the position of rest. To limit the downward movement of the connecting bar, a stop A⁸, is extended inward from the wall of the base, A, into the path of the horizontal portion of the connecting bar at the proper elevation to support said bar when the latter has moved downward 85 that far. When the plunger has been lowered to its limit, the operator again reverses the ratchet mechanism by forcing the pawl downward into its lower position. Then said mechanism can be worked for turning 90 the screw to again raise the plunger.

When the cam ring has been turned backward to its rest or normal position, the sleeve, E, may be moved inward to its normal position by the hand of the operator or 100 by the pressure of the arm, D¹³, of the pawl, D⁵, against the cam face, E³, on the sleeve, or such movement may be effected by the action of a spring, A⁹, secured by one end by a screw, A¹⁰, to the outer face of the 105 base, A, and bearing by its free end against an annular flange, E⁹, located on the inner end of the sleeve.

I claim as my invention,

1. In a lifting jack, the combination of a 110 base, a plunger, a screw parallel to the plunger for relatively lifting the plunger, a gear wheel on said screw, a second gear wheel in constant engagement with the first gear wheel for transmitting motion to the 115 latter, means for rotating the second gear wheel, a member movable in a path parallel to the path of the plunger and in operative relation with the latter to be moved in said path when the plunger moves to its upper 120 limit, and means placing said movable member into operative relation with said rotating means for automatically putting said means out of action during the upward movement of the plunger, substantially as 125 described.

2. In a lifting jack, the combination of a 130 base, a plunger, having an upright channel, a screw parallel to the plunger for relatively lifting the plunger, a gear wheel on

said screw, a second gear wheel in constant engagement with the first gear wheel for transmitting motion to the latter, means for rotating the second gear wheel, a member 5 movable endwise in said channel and in operative relation with said plunger to be moved in said channel when the plunger moves to its upper limit, and means placing said movable member into operative relation 10 with said rotating means for automatically putting said means out of action during the upward movement of the plunger, substantially as described.

3. In a lifting jack, the combination of a 15 base, a plunger, a screw parallel to the plunger for relatively lifting the plunger, a gear wheel on said screw, a shaft adjacent said screw, a second gear wheel on said shaft and in constant engagement with the first 20 gear wheel, means for rotating said shaft, a member movable in a path parallel to the path of the plunger and in operative relation with the latter to be moved in said path when the plunger moves to its upper limit 25 and means placing said movable member into operative relation with said rotating means for automatically putting said means out of action during the upward movement of the plunger, substantially as described.

30 4. In a lifting jack, the combination of a base, a plunger, a screw parallel to the plunger for relatively lifting the plunger, a bevel gear wheel on said screw, a rotary shaft perpendicular to said screw, a bevel 35 gear wheel located on said rotary shaft and in constant engagement with the other bevel gear wheel, driving means for rotating said rotary shaft, a member movable in a path parallel to the path of the plunger and in operative 40 relation with the latter to be moved in said path when the plunger moves to its upper limit, and means placing said movable member into operative relation with said driving means for automatically 45 putting said driving means out of action during the upward movement of the plunger, substantially as described.

5. In a lifting jack, the combination of a 50 base, a plunger having an upright channel, mechanism for relatively lifting said plunger, said mechanism comprising a rotary shaft perpendicular to said plunger and a pair of gears in continuous engagement with each other, one of said gears being on said 55 shaft, means for turning said shaft, a member movable in said channel and in operative relation with said plunger to be moved in said channel when the plunger moves to its upper limit, a sleeve concentric and 60 slidable parallel to said shaft, means operatively connecting said sleeve and said member which is movable parallel to the movement of said plunger, and means for placing said sleeve in operative relation with 65 said shaft-turning means for automatically

putting said turning means out of action during the upward movement of the plunger, substantially as described.

6. In a lifting jack, the combination of a 70 base, a plunger, mechanism for relatively lifting said plunger, said mechanism comprising a rotary shaft perpendicular to said plunger and a pair of gear wheels in continuous engagement with each other and one being mounted on said shaft, means for 75 turning said shaft, a connecting member adjacent the plunger, means on said plunger for engaging said member and moving it in unison with the plunger when the latter approaches its upper limit, a sleeve concentric to and slidable parallel to said shaft, means operatively connecting said sleeve and said connecting member, means for placing said sleeve in operative relation 80 with said shaft-turning means for automatically putting said turning means out of action during the upward movement of the plunger, substantially as described.

7. In a lifting jack, the combination of a 85 base, a plunger, mechanism for relatively lifting said plunger, said mechanism comprising a rotary shaft perpendicular to said plunger and means for rotating said shaft, a sleeve concentric with and slidable parallel to said shaft, means operable by the endwise 90 movement of said sleeve for placing said shaft-turning means out of action, a cam ring also concentric to said rotary shaft and in operative relation with said sleeve for moving the latter endwise by the partial rotation of said ring, and means operatively connecting said ring and the plunger for partially rotating the ring when the plunger 95 approaches its upper limit, substantially as 100 described.

8. In a lifting jack, the combination of a base, a plunger, mechanism for relatively lifting said plunger, said mechanism comprising a rotary shaft perpendicular to said plunger and means for rotating said shaft, a sleeve concentric with and slidable parallel to said shaft, means operable by the endwise 105 movement of said sleeve for placing said shaft-turning means out of action, a cam ring also concentric to said rotary shaft and in operative relation with said sleeve for moving the latter endwise by the partial rotation of said ring, a spring for returning said sleeve to normal or rest position, and means operatively connecting said ring and the plunger for partially rotating the ring 110 when the plunger approaches its upper limit, substantially as described.

9. In a lifting jack, the combination of a 115 hollow base, a plunger, mechanism for relatively lifting said plunger, said mechanism comprising a rotary shaft perpendicular to said plunger and means for rotating said shaft, a sleeve located outside the wall of the base and concentric with and slidable 120

parallel to said shaft, means operable by the endwise movement of said sleeve for placing said shaft-turning means out of action, a cam ring at the inner side of said wall and 5 also concentric to said rotary shaft and in operative relation with said sleeve for moving the latter endwise by the partial rotation of said ring, and means operatively connecting said ring and the plunger for partially 10 rotating the ring when the plunger approaches its upper limit, substantially as described.

10. In a lifting jack, the combination of a base, a plunger, mechanism for relatively 15 lifting said plunger, said mechanism comprising a rotary shaft perpendicular to said plunger and means for rotating said shaft, a cam ring concentric to said shaft, a member movable in a path parallel to the path 20 of said plunger and in operative relation with said cam ring for turning the latter when the plunger approaches its upper limit, and means operatively relating the cam ring and the shaft-turning means for placing the 25 latter out of action, substantially as described.

11. In a lifting jack, the combination of a base, a plunger, mechanism for relatively lifting said plunger, said mechanism comprising a rotary shaft perpendicular to said 30 plunger and means for rotating said shaft, a cam ring concentric to said shaft and bearing a stud, a member movable in a path parallel to the path of the plunger and in

operative relation with said stud for turning 35 said cam ring when the plunger approaches its upper limit and means operatively relating the cam ring and the shaft-turning means for placing the latter out of action, substantially as described. 40

12. In a lifting jack, the combination of a base, a plunger, mechanism for relatively lifting said plunger, said mechanism comprising a ratchet wheel and a pawl for engaging said ratchet wheel, and means in operative relation with said pawl and said plunger for transmitting motion from the plunger to said pawl for releasing the latter from the ratchet wheel when the plunger approaches its upper limit, substantially as 45 50 described.

13. In a lifting jack, the combination of a base, a plunger, mechanism for relatively lifting said plunger, said mechanism comprising a ratchet wheel and a pawl movable 55 in a path approximately tangential to said wheel, and means in operative relation with said pawl and said plunger for transmitting motion from the plunger to said pawl for the disengagement of the latter from the 60 ratchet wheel when the plunger approaches its upper limit, substantially as described.

In testimony whereof I have signed my name, in presence of two witnesses, this 4th day of April, in the year one thousand nine 65 hundred and sixteen.

LOCKE ATWELL.
